UNITED STATES PATENT OFFICE.

HANS BRETSCHER, OF NEW YORK, N. Y., ASSIGNOR OF ONE-HALF TO ALEXANDER PECORETTI AND ONE-HALF TO FRANZ MATZ, BOTH OF ELIZABETH, NEW JERSEY.

TROUSERS-STRETCHER.

1,362,839.

Specification of Letters Patent. Patented Dec. 21, 1920.

Application filed September 16, 1919. Serial No. 324,096.

To all whom it may concern:

Be it known that I, HANS BRETSCHER, a citizen of Switzerland, residing at New York city, in the county of New York and State 5 of New York, have invented certain new and useful Improvements in Trousers-Stretchers, of which the following is a specification, reference being had to the accompanying drawings.

10 This invention relates to trousers stretchers, and has for its object to provide a device of this character which efficiently stretches the trousers through the medium of stretching elements having outwardly bowed sides and ends.

Another object is to provide a device of this character including two stretching elements formed from two lengths of wire and connected to each other, the connecting sides 20 of each element including outwardly bowed portions which serve to increase the stretching power of the elements and tend to resist contraction when the stretching elements are moved toward each other for application to the trousers legs.

These objects are attained by the mechanism illustrated in the accompanying drawings, in which:

Figure 1 is a vertical elevation of the 30 stretcher applied to a pair of trousers;

Fig. 2 is a plan view of the stretcher in its expanded position;

Fig. 3 is a detail view of the connected ends of the stretching elements of the 35 stretcher;

Fig. 4 is a side elevation of the clamp applied to the ends of the stretching elements, the ends being shown in section.

Referring to the drawings, 5 indicates one 40 stretching element and 6 the other stretching element. Each stretching element is formed from a single length of wire which is bowed at its intermediate portion 7 and bent, as at 8, in angular relation to the intermediate portion 7, to provide bowed ends 9. The ends are bent, as at 10, in angular relation to the end portions 9 to provide bowed sides 11, the free ends 12 of the wire being bent in angular relation to the sides 11. By 45 the novel bowed arrangement of the sides 7 and 11 and ends 9, an expanding power is created which serves to increase the stretching power of the stretcher.

In assembling the stretcher, the ends 12 of the element 5 are disposed between the 55 ends 12 of the element 6 and are secured to each other by means of a clamp 13. The clamp 13 comprises a casing 14 bent to provide sides 15, the free ends 16 of the casing being bent upon themselves to provide 60 flanges 17. A connecting plate 18 is intended to connect the flanges 17 of the clamp and comprises an inwardly bowed base portion 19 and upwardly and inwardly extending ends 20, the inwardly extending 65 ends serving to provide flanges 21 adapted to engage the flanges 17 of the clamp.

As shown in Fig. 4, the base portion 19 of the connecting plates serves to force the ends 12 of the stretching element 5 into engagement with the wall of the clamp and at the same time to cause the sides 15 of the clamp to engage the ends 12 of the stretching element 5 and also force the latter into engagement with the ends 12 of the stretching 75 element 5 so that it is impossible for the ends, in view of this novel clamping arrangement, to become accidentally disengaged from each other. In order to properly support the trousers stretcher, a chain 22 is 80 connected at one end to the stretching element 6 and at its other end to the stretching element 5 and includes a ring 23 at its intermediate portion to be engaged with any suitable supporting means. This chain, while it 85 efficiently supports the stretcher, does not interfere in any manner with the expanding power of the stretching elements.

In use, one of the stretchers comprising the stretching elements 5 and 6 is intended 90 to be disposed in each leg of the trousers and is applied by contracting the elements 5 and 6 so that the sides 11 of each element cross each other, and in view of their bowed arrangement, the crossing tends to distort 95 the bowed portion and thereby increases the stretching power of each stretching element. At the same time, the sides 7, in view of their bowed arrangement, readily conform to the shape of the trousers and engage the 100 latter at all points along its entire surface.

In view of the fact that each stretching element of the stretcher is formed from a separate length of wire, one stretching element does not decrease the stretching power 105 of the adjacent stretching element. In ad-

dition to this, the ends of each element, being clamped to each other, form a substantial connection.

I claim:—

- 5 1. A trousers stretcher comprising two lengths of wire, each bent to provide outwardly bowed side and end portions, the free ends of said wire extending in right angular relation to the side portions of said wire, the ends of one wire being disposed between the ends of the adjacent wire, and a clamp for binding said ends to each other, said clamp preventing oscillating movement of said ends within the clamp.
- 10 10. A trousers stretcher comprising two lengths of wire, each length being bent at its intermediate portion to provide a stretching element, the ends and intermediate portion being outwardly bowed, the ends of one
- 15 15. A trousers stretcher comprising two lengths of wire, each length being bent at its intermediate portion to provide a stretching element, the ends and intermediate portion being outwardly bowed, the ends of one

wire engaging each other and interposed between the ends of the adjacent wire, a clamp comprising a casing partially surrounding the ends of both wires, the ends of the clamp being bent to provide flanges, a connecting plate having upwardly and inwardly extending ends engaged with the flanges of the clamp, the body portion of the connecting plate engaging the first mentioned engaged ends of one of the wires to force the same into engagement with the wall of the clamp, the connection of the plate to the clamp serving to force the second named wire into engagement with the sides of the clamp and the first mentioned wire ends.

In testimony whereof I hereunto affix my signature.

HANS BRETSCHER.
